UNITED STATES PATENT OFFICE.

AIME GAUTHIER, OF WILLOW CITY, NORTH DAKOTA.

HORSESHOE.

1,191,413.

Specification of Letters Patent.

Patented July 18, 1916.

Application filed May 21, 1915. Serial No. 29,638.

To all whom it may concern:

Be it known that I, AIME GAUTHIER, a citizen of the Dominion of Canada, residing at Willow City, in the county of Bottineau, 5 State of North Dakota, have invented certain new and useful Improvements in Horse-shoes; and I do hereby declare the following to be a full, clear, and exact description of the invention, such as will enable others skilled in the art to which it appertains to 10 make and use the same.

This invention relates to a horse shoe.

An object of the invention resides in the provision of a device which includes a plurality of removable calks.

A further object of the invention resides in so constructing the device that the calks may be removed without necessitating the removal of the shoe from the horse's foot. 20 A still further object of the invention resides in so constructing the calks that the bearing portions thereof will be of hard metal and carried by soft metal body portions.

With these and other objects in view, such as will appear as the description progresses, my invention comprises the combination and arrangement of parts as set forth in and falling within the scope of the appended claims. 25

Referring to the drawing: Figure 1 is a bottom plan view of a shoe constructed in accordance with my invention, a shoe which is used in a right foot of a horse being shown. Fig. 2 is a rear elevation of the shoe. Fig. 3 is a side elevation thereof. Fig. 4 is a fragmental detail of the toe calk and the forward portion of the shoe, showing the manner of mounting the calk on the shoe. Fig. 5 is a bottom plan view of a modification of 40 my device. Fig. 6 is a rear elevation thereof.

Referring to the drawing wherein like parts are indicated by like characters throughout the several views:—In the embodiment of my invention shown in the drawings I have illustrated my device as consisting of a shoe 1 which has enlargements 2 and 3 on the lower face of the ends thereof and an enlargement 4 at the toe portion thereof. The enlargement 2 is provided 45 with a socket 5 which extends transversely of the shoe and is of dove-tail formation. Detachably mounted in this socket 5 is a wedge-shaped calk 6 which consists of a body portion made of soft metal and a bearing plate 7, which bearing plate is of uni-

form thickness throughout. Thus as the calk is subjected to wear the body portion will wear quicker than the bearing plate and consequently a portion of the plate will always be exposed to penetrate the ground. 60 This calk is held in place by a set screw 8 which passes through and in threaded engagement with the enlargement 2. The body portion of the calk is provided with a depression 9 into which the inner end of the 65 set screw 8 extends so as to prevent the displacement of the calk from the shoe and bind it in place. This set screw is provided with a squared head as shown in the drawing for the reception of a wrench.

Mounted in the enlargement 3 is a socket 10 therein, which is of formation similar to the socket 5, but extends from the front to the rear of the shoe, is a calk 11 which is similar in formation to the calk 6 and is provided with a bearing plate 12. This calk 11 is maintained in place by a set screw 13. Mounted in a socket 14 in the enlargement 4 and extending transversely of the shoe is a calk 15 which is provided with a bearing plate 16 and is maintained in place in the said socket by a set screw 17.

The calk 11 which is located on the outside of the foot of the horse is slightly longer than the calk 6 as it has been found by experience that the outside calk will wear faster than the inside calk.

It will thus be seen that the calks are all in place and secured by the set screws so that the horse's foot will be prevented from slipping in any direction. It will further be seen that by providing a soft metal body portion for each of the calks and a hard metal bearing plate of decreasing thickness that a portion of the bearing plate will always be exposed until it is entirely worn away and this exposed portion will be of such thickness that it will readily penetrate or grip the ground.

In the embodiment of my invention shown in Figs. 5 and 6 of the drawing I have omitted the calks 6 and 11 and have replaced them by the following structure: A pair of arms 18 and 19 are pivoted together on a removable bolt 20. Formed on the end of the arm 18 is a calk 21 having a bearing plate 22 therein, which calk is adapted to fit into the socket 5 of the shoe 1. On the other arm 19 is formed a calk 23 which includes a bearing plate 24 and which calk is adapted to fit into 110

the socket 10 in the enlargement 3 and to be secured therein by the set screw 13. The arms 18 and 19 extend forwardly between the arms of the shoe 1 and form a protector 5 for the bottom of the horse's foot.

From the foregoing description it will be seen that I have provided a horse shoe which includes a plurality of calks so arranged that the slipping of the horse's foot in any direction will be prevented and I have constructed each of the calks so that it includes a soft metal body portion and a relatively harder metal bearing blade.

While I have illustrated and described a particular embodiment of my invention, I have merely done so for the sake of convenience and I do not wish to be limited to that particular embodiment as it is obvious that numerous changes may be made within the details of construction thereof without in any way departing from the spirit of the invention or exceeding the scope of the appended claims.

What I claim is:

25 1. The combination with a horse shoe having sockets in the ends thereof, of calks detachably mounted in said sockets, integral

arms extending from said calks and means for securing the arms together.

2. The combination with a horse shoe having a socket in one end thereof extending longitudinally of the adjacent side and a socket in the other end thereof extending transversely of the adjacent side, of calks detachably mounted in said sockets, arms extending from said calks and means for securing the arms together.

3. The combination with a horse shoe having a socket in one end thereof extending longitudinally of the adjacent side and a socket in the other end thereof extending transversely of the adjacent side, of calks detachably mounted in said sockets, arms extending from said calks and inwardly from the ends of the shoe and means for securing the arms together.

In testimony whereof, I affix my signature, in the presence of two witnesses.

AIME ^{his} X GAUTHIER.
